UNITED STATES PATENT OFFICE.

CHARLES W. GLIDDEN, OF LYNN, ASSIGNOR TO JAMES W. BROOKS,
TRUSTEE, OF PETERSHAM, MASSACHUSETTS.

NAIL-ASSORTING MACHINE.

SPECIFICATION forming part of Letters Patent No. 498,429, dated May 30, 1893.

Application filed July 23, 1892. Serial No. 441,021. (No model.)

To all whom it may concern:

Be it known that I, CHARLES W. GLIDDEN, of Lynn, county of Essex, State of Massachusetts, have invented an Improvement in Nail-Assorting Machines, of which the following description, in connection with the accompanying drawings, is a specification, like letters and figures on the drawings representing like parts.

10 This invention has for its object to improve the construction and operation of that class of machine shown in United States Patent No. 464,196, granted to me December 1, 1891, whereby the machine is simplified, and without removal of parts may be quickly adapted for handling nails of different length. The patent referred to represents the nails as being put into what are called pools by elevators represented as bars adapted to be reciprocated vertically in the hopper or pool containing the nails in mass. In practice it was found desirable to so shape the upper edges of these elevator bars as to form pockets for the nails, such pockets being substantially of the length 25 of the nails, thereby avoiding the overlapping of nails on the edge of the elevator, overlapping of the nails interfering with their correct discharge into the pools. The pockets overcame the trouble due to overlapping, but 30 it was found necessary to have a number of these elevator bars and provide them with pockets of different length to accommodate the particular length of nail to be used. To further improve the machine, I devised a compound elevator, or an elevator composed of 35 two bars lying side by side, each bar having a series of prongs or uprights so shaped as to fall in substantially the same horizontal plane or line so that when the said bars were adjusted one with relation to the other longitudinally the said prongs would be made to approach or recede from each other in pairs, and thus constitute pockets of the length desired for the nail to be handled. In the machine referred to, the parts containing the pools had also to be changed to correspond with the particular length of nail to be used, but herein I have devised means whereby the length of the pools may readily be simultaneously and symmetrically adjusted to the length of the nail.

Figure 1, is a plan view of a nail assorting mechanism embodying my invention, some of the devices at the right-hand side of the machine supposed to be exactly as at the left, 55 being omitted. Fig. 2, is an end view of a sufficient portion of a nail assorting mechanism to enable my invention to be understood the left-hand half of the machine being shown in section in the line x' of Figs. 1 and 5, to 60 better illustrate its interior construction, the machine in practice containing at both sides like devices. Fig. 2^a, is a detail of part of the driver plate d . Fig. 3, is a plan view of that part of the machine to the left of the dotted line x' , Fig. 1. Fig. 4, is an enlarged detail showing the adjusting devices for the pool detached and reversed from the position shown in Fig. 3. Fig. 5, is a detail showing in plan view the adjusting devices for the elevators. 65 Fig. 6, in elevation shows part of the lifter detached. Fig. 6^a, is a detail showing the upper end of the discharging device, and one of the lifters; and Fig. 7, is a detail showing the compound elevator with its plates somewhat separated, the figure being reduced about one-half from the scale of Fig. 5.

In the drawings, A represents a stationary frame-work, and it may be of any suitable shape to sustain the working parts to be described, and it may be sustained in any suitable manner.

The frame-work has suitable tracks or guide-ways A' for a reciprocating table B, one half of which is shown in section in Fig. 2, said 85 table in practice having a gigging or shaking motion imparted to it in some suitable manner as herein provided for by a connecting rod B' embracing a crank or eccentric on a suitable shaft B² actuated in any usual or 90 suitable manner. This table contains several sets or series of like devices to enable the desired number of headless nails to be assorted and directed point first, and it therefore becomes unnecessary to specifically describe 95 more than one set of the like devices. The table referred to has like side walls B⁴, and like end walls B⁵.

Commencing at the left of the drawings Figs. 1 and 2, C represents a hopper or receptacle for the nails in bulk. This receptacle has two like long slots, but I will describe only

one of these, and in my description work toward the left in Fig. 2, the parts at the right of the receptacle being just the same as at the left. The said slot in the bottom of the hopper receives what I have called a compound elevator, it being composed of two plates a , b , fitted closely together, and each provided with a series of projections as a' , b' , the projections a' being so shaped as to overlap and fit the beveled upper edge of the plate b , while the projections b' are so shaped as to overlap the beveled upper edge of the plate a , the said edges being shown as of the same—coinciding bevel, such construction of the projections a' , b' , leaving them in the same path of movement so as to constitute like end walls for nail pockets, the pockets being the spaces left between the acting faces of the said projections, and consequently by adjusting these plates longitudinally one with relation to the other, pockets of any desired length may be constructed, the length of the pockets depending on the length of the nails to be used. To adjust these plates thereon, I have in this present embodiment employed devices which I will now describe. Below the bottom of said hopper portion I have located a right and left threaded screw c , and to prevent longitudinal movement thereof during its rotation, I have provided the said screw with a suitable annular space as c' which is entered by suitable bearing blocks c^2 fixed to a spider D having a shank D' which in practice will be reciprocated for a short distance vertically in the sleeve or bearing A^2 forming part of the frame-work. It may be so reciprocated by a sector lever A^2 , partially shown in Fig. 2, and engaging the shank D' , said lever deriving its movement from any suitable source. The plates a , b , are provided respectively with slots a^4 , b^4 , and with holes a^5 , b^5 . The reversely threaded parts of the screw c enter respectively threaded blocks c^3 , c^4 , provided at opposite ends with like pins, one of which is marked 4 and the other 5. In Fig. 7, the plates a , b , are reversed end for end from the position Fig. 5, where the said plates are lettered. The pin 4 enters the hole a^5 and acts to move the plate a , while the pin 5 passes through the slot a^4 and enters the hole b^5 in plate b and moves it, the slot permitting movement of one plate without contact with the pin moving the other plate. Providing each plate with like slots, enables the plate to be used interchangeably at either side of the hopper. The screw c in practice has, see Figs. 2 and 3, a milled head c^x by which to rotate it.

Next to the left of the compound adjustable elevator is an upright or division wall d , a portion of the upper edge of which is shown in perspective in Fig. 2^a, said division wall having a longitudinal groove t to form the bottom of certain pools, to be described, into which the nails are deposited by the elevator described, said groove being intersected by a series of vertical holes 6, 7, 8, in which are fitted to slide vertically, the lifters h , h' , and

the discharging device i , see detail Fig. 6, the lifters being connected to a bar h^2 , while the discharging devices are connected to a bar h^3 just below it, the bar h^3 being supported in a yielding manner above the bar h^2 in this present instance of my invention by springs h^4 , pins h^5 acting as guides for the bar h^2 .

The central lifter h' is represented as semi-cylindrical to co-operate with the discharging device i of like shape, their flat sides working together, their upper ends being beveled preferably in opposite directions so as to form a fork or notch. The upper ends of the lifters h , are notched in the direction of the length of the bar h^2 , said notches as the upper ends of the lifters rise from the bottom of the pool acting to properly support and carry a nail. When the lifters start to rise with a nail the upper ends of the lifters and the discharging devices are at the same level, but after the spider D has been lifted sufficiently to enable the lifters to bring the nail up to the upper edge of the bar m over which they are to be cast point first, the bar h^2 meets and is arrested by the under side of the slide B , the spider in its further movement, however, lifting the bar h^3 and with it the discharging device i which contacts with the nail at the middle of its length, said nail resting on the lifters h , and by its inclined upper end causes the nail to be moved laterally from the lifters over the upper edge of the bar m , but to insure the passage of the point of the nail across said bar in advance of the crossing of the head of the nail I have provided two stops 12, 13, against one of which, the head of the nail being lifted at its middle, by the discharging device, will act and be thereby held back while the lighter or point-end of the nail is lifted and pushed over the other projection. The point end of the nail having passed the stop adjacent to it is left free to drop into the mouth n located at one side of the bar m , the nail so dropped point first passing through the said mouth and entering a guide or funnel n' at the upper end of a nail conducting or guiding tube or roadway n^2 leading to the point where it is desired to deposit the nail. The upright d is capped by the bar m , it having a narrow thin upper edge and beveled or inclined on its discharging side as at the left in Fig. 2. This bar m is embraced by a series of movable partition walls o , o' , connected respectively with parallel slide bars o^2 , o^3 , each made simultaneously adjustable in opposite directions by a right and left screw p , in nuts o^4 , o^5 , of said bars. These partition walls are extended below the back or rear side of the bar m and are so shaped as herein shown as to enter and fit the groove t made in the upper end of the division wall d , so that as the said screw is rotated in one or the other direction the said division walls are made to recede from or approach each other to thus make the space between each co-operating pair of division walls of greater or less width to adapt the series of

pools to the length of the nails being used. The stops 13, 14, referred to, are attached to the division walls and are adjustable in unison with them. The mouths referred to, are shown as separate blocks having handles *r*, by which they may be removed from the machine in case it is desired to not use any one roadway, the hole in the slide B left by removing a roadway or mouth, being suitably corked or plugged.

Believing myself to be the first to make a lifter in two or more parts so that one part may be moved on or with relation to the other to form nail pockets of desired length, and also believing myself to be the first to use a series of nail pools which have adjustable walls, this invention is not to be limited to the exact construction shown for said mechanism as the same might be variously modified in shape and yet not depart from my invention.

Having described my invention, what I claim as new, and desire to secure by Letters Patent, is—

1. In a nail assorting mechanism, a nail elevator provided with projections to divide the same into pockets, combined with adjusting devices to lengthen or shorten said pockets as desired to adapt them to the length of nail being used, substantially as described.

2. In a nail assorting mechanism, a hopper or receiver for nails in bulk, and a pool, combined with a nail elevator composed of two or more parts adjustable each with relation to the other to provide the elevator with longer or shorter pockets according to the length of nails to be used, substantially as described.

3. In a nail assorting machine, a pool, combined with end walls and adjusting devices to adjust the said end walls relatively to each other to adapt the length of the pool to the length of the nail being used, substantially as described.

4. The combination with a slide having a hopper or nail receiver, of a nail elevator composed of two plates placed side by side and having projections, the projections of one plate overlapping the other plate, and vice versa, and a right and left hand screw device to adjust the said plates one with relation to the other longitudinally, substantially as described.

5. A nail assorting mechanism containing the following instrumentalities, viz:—a slide having a hopper or receptacle for nails in bulk, a compound elevator, means to adjust it to lengthen and shorten the pockets thereof to the requirements of the nail being used, a pool into which the elevator deposits a nail

lifted by it, a series of lifters, adjustable end walls for the pool and between which end walls the said lifters are adapted to rise and fall, a discharging device, a discharging bar as *m*, and a mouth to receive and guide nails point first, substantially as described.

6. In a nail assorting mechanism, a discharging wall over which nails are to be discharged, a pool at one side of the wall, a series of lifters, and a discharging device adapted to be reciprocated vertically in the said pool to lift a nail, devices to impart additional vertical movement to the discharging device, and stops co-operating with the head of the nail to prevent it from being moved laterally while the point end of the nail acted upon near its center is being lifted by the discharging device, whereby the discharge of the nail point foremost is insured, substantially as described.

7. In a nail assorting machine, a discharging bar having at one side a nail pool, lifting devices, and a discharging device adapted to be reciprocated vertically in said pool to lift and discharge a nail, combined with stops 13, 14, and devices to adjust the same toward and from each other to adapt them to the length of nail being used, to operate, substantially as described.

8. In a nail assorting machine, a discharging bar having at one side a nail pool, lifting devices, and a discharging device adapted to be reciprocated vertically in said pool to lift and discharge a nail, combined with stops to arrest the head end of the nail as the nail is being discharged point foremost, substantially as described.

9. In a nail assorting mechanism, a lifting device adapted to lift loose nails singly and support them in horizontal position; and a co-operating nail discharging device; combined with a stop to retard the movement of the head of the nail while the discharging device acts to discharge the nail point-first from the lifting device, substantially as described.

10. In a nail assorting mechanism, a support for the opposite ends of a nail while in horizontal position; and two stops for the sides of the nail, one being located near the head and the other near the point end of the nail, combined with a discharging device to effect the discharge of the nail point-first, substantially as described.

In testimony whereof I have signed my name to this specification in the presence of two subscribing witnesses.

CHARLES W. GLIDDEN.
